UNITED STATES PATENT OFFICE.

HAROLD J. BELL, OF GLOUCESTER CITY, NEW JERSEY, ASSIGNOR TO THE WELSBACH INCANDESCENT GAS LIGHT COMPANY, OF NEW JERSEY.

GAS-PRESSURE REGULATOR.

SPECIFICATION forming part of Letters Patent No. 409,627, dated August 20, 1889.

Application filed June 6, 1889. Serial No. 313,327. (No model.)

To all whom it may concern:

Be it known that I, HAROLD J. BELL, a citizen of the United States, residing at Gloucester City, in the county of Camden and State of 5 New Jersey, have invented new and useful Improvements in Gas-Pressure Regulators, of which the following is a specification.

The object of my invention is to improve the construction of that class of high-pressure 10 gas-regulators which are especially adapted to be employed between the gas-meter and the supply-main, though also capable of use elsewhere; and the invention consists in a gas-pressure-regulating apparatus comprising 15 an outer casing or main chamber having an inlet, an outlet, and a vent, an inner chamber having upper and lower gas-passages and valve-seats and an intermediate by-pass, automatic safety cut-off and pressure-regulating 20 valves, a flexible diaphragm having an automatic safety relief-valve, cam-lever connections between the said diaphragm and cut-off valves, and a starting-valve for controlling the by-pass.

25 The invention will be first particularly described, and then pointed out in the claims.

In the annexed drawings, illustrating the invention, Figure 1 is a vertical sectional elevation of a high-pressure gas-regulator employing my improvements. Fig. 2 is a section at a right angle to Fig. 1, both views showing the valves closed by the weight of the diaphragm and attached parts. Fig. 3 is a detail view showing the position of the cam 30 when the valves are wide open. Fig. 4 is a detail view showing the position of the cam when the valves are closed by gas-pressure under the diaphragm.

Referring to the drawings, the numeral 1 40 designates a casing or chamber having a removable cover 2, which is provided with a vent 3 in its top. In the lower part of the casing 1 is an outlet 4, opposite which is an opening for an inlet-pipe 5, that projects into 45 the casing and has an inner chamber or valve-seat casing 6 on its inner end. The inlet-pipe 5 is held in place by a nut 7, and is adapted to connect with a gas-supply pipe. A screw 7^a, passed diagonally through the 50 casing 1 and pipe 5, prevents said pipe and

attached inner chamber 6 from turning. The inner chamber 6 is provided at top and bottom with flanged openings 8 and 9 for the passage of gas. In the upper part of the casing or chamber 1 is a flexible diaphragm 10, composed of leather or other suitable material, having its outer edge secured between the body and cover of the casing. This diaphragm is provided with a central rigid portion 11, of annular form, in the center of 60 which is secured a tubular laterally-perforated casting or valve-casing 12, screw-threaded for attachment of a cap 13, by which said diaphragm and valve-casing are connected. In the top of the cap 13 is an opening having inwardly and downwardly beveled edges to receive a weighted safety relief-valve 14, which is partly conical and partly cylindrical, as shown. This valve protects the flexible diaphragm 10 from the injurious effect of excessive pressure. The lower part of 65 the casting 12 is provided with lateral openings 15 for the passage of gas to the relief-valve. Attached to the casting 12 is a depending rod 16, the lower end of which connects with the arm 17 of a lever 18, having a cam-slot 19, that engages an anti-friction roller 20, which is supported in suitable bearings 21, connected with the safety cut-off and regulating valves. These valves are two in number—an upper valve 22 above the chamber 6 and a lower valve 23 within said chamber. The valves 22 and 23 consist of elastic disks 80 that are connected in any suitable manner with an intermediate stem 24, and are provided with wing-guides 25, that move vertically in the gas-passages of the inner chamber 6, which is provided with standards 26, with which the cam-lever 18 is pivotally connected. The chamber 6 is provided in one 85 side with a by-pass opening 27, leading into the outer casing or chamber 1 between the two cut-off and regulating valves. This by-pass 27 is controlled by an adjustable and independent starting-valve 28, having a screw-threaded engagement with the outer casing. If desired, a stuffing-box 29, provided with 90 suitable packing, may be placed around said valve, as shown.

When the apparatus is placed in position, 100

the valves 22 and 23 are closed by gravity against their seats at the upper edges of the gas-passages 8 and 9 of the inner chamber 6, the flexible diaphragm 10 and intermediate valve-connections being in the position shown in Figs. 1 and 2. Owing to the weight of the lowered diaphragm and connected valves, it is obvious that the chamber 6 will not be able to exert sufficient pressure on the under side of the upper valve 22 to overcome the downward pressure on the upper side of the lower valve 23, and therefore these valves 22 and 23 will remain closed until the starting-valve 28 is opened to permit the passage of sufficient gas to exert a lifting-pressure on the under side of the diaphragm. After the valves 22 and 23 have been started the valve 28 should be adjusted to permit the passage of only a small quantity of gas—say one cubic foot per hour, which will be sufficient to provide for starting the valves 22 and 23 automatically by closing the burner when the gas has been again turned on after it has been withdrawn or cut off from the regulator by accident or otherwise. If the supply of gas to the regulator should be withdrawn while the burners are in use, thereby removing pressure from the under side of the diaphragm 10, the valves 22 and 23 will at once close by gravity, as shown in Figs. 1 and 2, and prevent the escape of gas into the building, except the inconsiderable quantity that will flow through the by-pass 27 when the supply is restored. By closing the burners the gas admitted through the by-pass will accumulate beneath the diaphragm in sufficient quantity to exert a lifting-pressure that will start the valves 22 and 23 from their seats and carry them into operative position for controlling and regulating the pressure of gas delivered through the apparatus. While the valves 22 and 23 are in this position the cam 18 is substantially horizontal, as shown in Fig. 3, the anti-friction roller 20 being thus engaged with the central portion of the cam-slot. If the pressure of gas should become excessive, the diaphragm 10 will be forced farther upward, thereby actuating the cam in such a manner that the end of its slot 19 opposite the lever-arm 17 will engage the roller 20 and force the valves 22 and 23 downward toward or onto their seats, as shown in Fig. 4, thus nearly or quite closing the gas-passages, so as to diminish the pressure of gas delivered. As soon as the gas-pressure is thus moderated the diaphragm 10 will descend and restore the valves 22 and 23 to their normal operative position. It will be seen that by means of the cam-lever connection between the diaphragm 10 and the valves 22 and 23 said valves are given a positive movement that insures an effective automatic operation in regulating the pressure and in closing the valves 22 and 23, both at an excessively high pressure and when the gas is withdrawn or cut off from the regulator. The liability of accident and the waste, inconvenience, and danger of the es-

cape of gas into a building are thus greatly lessened.

By referring to Figs. 2 and 3 it will be seen that the flexible or elastic cut-off and regulating valves 22 and 23 are in annular form and are secured to the flanged ends of the stem 24 by means of flanged blocks 30 and 31, that are fastened to the ends of the intermediate valve-stem by screws 32 in axial line with the stem. Each block 30 and 31 is formed at one end or side with a central boss 33, that enters the central opening of the annular valve, and so secures it in place without exerting undue compression on the elastic substance of said valve. The lower block 30 carries the wing-guides 25 of the lower valve, while the guides of the upper valve are formed on or carried by the upper end of the valve-stem. The flanged upper portion of the stem 24 and the flanged portion of the lower block 30 are beveled, as shown, beneath the respective upper and lower elastic valves, to enable them to seat tightly. The upper block 31 carries the bearings 21 of the anti-friction roller 20, which is engaged in the cam-slot 19 of the lever 18, said roller being journaled by means of a pin 34, having nuts 35 on its ends to facilitate its insertion and removal. The standards 26 have preferably a screw-threaded connection with the top of the inner chamber 6, and their upper ends are screw-threaded for attachment of a two-part cross-bar 36, that is adjustably held in place on the standards 26 by means of nuts 37, and is separable at its center to facilitate the attachment and centering of the cam-lever 18, through which the cut-off and pressure-regulating valves are actuated. By means of the centrally-separable two-part cross-bar 36, on which the cam-lever 18 is fulcrumed, said lever can be accurately centered in position and be readily removed when desired, and by means of the nuts 37 it can be adjusted vertically as may be required to cause the valves 22 and 23 to seat properly. By making these valves of rubber or other suitable elastic material, they are enabled to close the gas-passages 8 and 9 tightly, and their action will not be affected by any gritty deposit on the valve-seats.

What I claim as my invention is—

1. In a gas-pressure regulator, the combination, with a casing or chamber having a flexible diaphragm, an inner chamber having gas-passages communicating with the said casing or outer chamber, and automatic safety cut-off and pressure-regulating valves for controlling said gas-passages, of cam-lever connections between said diaphragm and valves, substantially as described.

2. In a gas-pressure regulator, the combination of an outer chamber or casing, an inner chamber having gas-passages communicating with the outer chamber, automatic safety cut-off and regulating valves, an anti-friction roller connected with said valves, a cam having a slot engaged with said roller, a flexi-

ble diaphragm, and a rod or lever connecting the said diaphragm and cam, substantially as described.

3. In a gas-pressure regulator, the combination of the casing 1, the flexible diaphragm 10, having a depending rod 16, the chamber 6, having gas-passages 8 and 9 and by-pass 27, the safety cut-off and regulating valves 22 and 23, roller 20, cam 18, and starting-valve 28, substantially as described.

4. In a gas-pressure regulator, the combination of the flanged valve-stem 24, the annular elastic valves 22 and 23, and the flanged blocks 30 and 31, for securing the valves to said stem, substantially as described.

5. In a gas-pressure regulator, the combination of the flanged stem 24, having guides at one end, the annular elastic valves 22 and 23, the flanged block 30, provided with guides 20 and having a central boss that engages the lower valve, the flanged block 31, having a central boss engaged with the upper valve, and means for securing said blocks to the

ends of the valve-stem, substantially as described.

6. In a gas-pressure regulator, the combination, with the diaphragm 10, the elastic valves 22 and 23, and the stem 24, to which said valves are secured, of cam-lever connections between the diaphragm and valves, substantially as described.

7. In a gas-pressure regulator, the combination of the standard 26, the adjustable two-part cross-bar 36, the lever 18, centered on said cross-bar and provided with a cam-slot 35 19, the anti-friction roller 20, engaged in said slot, and the valves 22 and 23, having a stem that carries bearings for said roller, substantially as described.

In testimony whereof I have affixed my signature in presence of two witnesses.

H. J. BELL.
